(57) CLAIM

The ornamental design for a texturing tool, as shown and described.

DESCRIPTION

FIG. 1 is a front perspective view of a texturing tool according to a first example embodiment;

FIG. 2 is a bottom plan view thereof;

FIG. 3 is a front elevation view thereof;

FIG. 4 is a top plan view thereof;

FIG. 5 is a left side elevation view thereof;

FIG. 6 is a right side elevation view thereof;

FIG. 7 is a back side elevation view thereof; and,

FIG. 8 is a bottom perspective view thereof.

The broken line in the figure drawings represents unclaimed portion of the design and forms no part of the claim.
